(57) **CLAIM**

The ornamental design for a cutting tool, as shown and described.

DESCRIPTION

FIG. 1 is a front view of a cutting tool in accordance with the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a cross sectional view taken along line 9-9 of FIG. 1;

FIG. 10 is a cross sectional view taken along line 10-10 of FIG. 1;

FIG. 11 is a cross sectional view taken along line 11-11 of FIG. 1;

FIG. 12 is a cross sectional view taken along line 12-12 of FIG. 1;

FIG. 13 is a cross sectional view taken along line 13-13 of FIG. 1;

FIG. 14 is a cross sectional view taken along line 14-14 of FIG. 1;

FIG. 15 is a cross sectional view taken along line 15-15 of FIG. 1; and,

FIG. 16 is an enlarged view of portion 16 of FIG. 1.

(Continued)

The dashed-dot-dashed lines in FIG. 1 and FIG. 16 indicate enlarged portions and form no part of the claimed design.

1 Claim, 8 Drawing Sheets
